LIQUIDIZER

Walter E. Moore, Belnord, Mo., assignor to Knapp-Mon-
arch Company, St. Louis, Mo., a corporation of Dela-
ware

Application May 10, 1954, Serial No. 30,391

Term of patent 14 years

(Cl. D89—1)

Figure 1 is a perspective view taken from one side of a liquidizer embodying my new design;

Figure 2 is a side elevational view on an enlarged scale of the liquidizer shown in Figure 1; and

Figure 3 is a fragmentary perspective view on a reduced scale taken from the side opposite Figure 1.

The essential features of my design reside in the portions shown in full lines.

I claim:

The ornamental design for a liquidizer, substantially as shown and described.
